DICTATING MACHINE

Benjamin A. Schiff, Chicago, Ill.

Application February 21, 1940, Serial No. 320,046

1 Claim. (Cl. 274—17)

My invention relates to a sound recording and reproducing machine for commercial dictating use.

Among the objects of my invention is to provide a dictating machine having push button control for setting the device in receiving, reproducing and neutral positions. My controls are so constructed that a record cannot be withdrawn or placed onto the mandrel unless the machine is in neutral position, thus preventing damage to the stylus and record. The push buttons of my control members are visible at all times and the user may always know the position of the machine by seeing the position of the buttons. My device is easy to manipulate, rapid and certain in operation, economical in construction and lasting in wear. My push button construction also eliminates old, bulky and now unnecessary parts. My push button controls are compact and are located in a convenient position for operation, away from accidental and damaging contact by the user with the record. My controls also act to definitely lock the machine in recording, reproducing or neutral position, to remain in such position until changed by the user, and such other objects, advantages and capabilities as will more fully appear and which are inherently possessed by my invention.

While I have shown in the accompanying drawings a preferred embodiment of my invention, yet I wish it understood that the same is susceptible of modification and change without departing from the spirit of my invention.

Referring more particularly to the drawings, Fig. 1 is a top plan view of my dictating machine; Fig. 2 is an end elevation in section on line 2—2 of Fig. 1; Fig. 3 is a front elevation on line 3—3 of Fig. 1; Fig. 4 is an enlarged sectional view of the push buttons and jewels; Fig. 5 is an end elevation looking in the direction of the arrow in Fig. 4; Fig. 6 is a vertical staggered sectional view through the sound carriage and neutral control member; Fig. 7 is a vertical sectional view through the sound carriage at the dictate position; Fig. 8 is a vertical staggered sectional view through the sound carriage and the listen control member.

The embodiment selected to illustrate my invention comprises a frame 10 having a vertical support 11 rotatably supporting a shaft 12 upon which is mounted a rotatable mandrel 13. The shaft 12 is connected to a driving wheel 14 moved by a belt 15 driven by a suitable power such as an electric motor 16.

A sound recording and reproducing member

17 has a carriage 18 slidable on a rod 19 attached on either end to upstanding portions 20 of frame 10. The sound member 17 has a cutting stylus 21 for contacting a wax cylinder 22 when the same is in position on said mandrel 13.

Attached to the under portion of the frame 10 is a housing 23 having on opposite ends spaced upper and lower slots 24 and 25 respectively to receive upper and lower shank portions 26 and 27 respectively of control members 28. Said control members 28 have buttons 29 attached to the upper ends of their upper shank portions 26. Said buttons 29 may be marked "Neutral," "Dictate" and "Listen," or other suitable descriptions. Each of said control members 28 has an upper shank portion 26 extending within the upper slots 24 of housing 23. Immediately below the upper shank portions 26 of said control members 28 have an enlarged body portion 30, and below said body portion a lower shank portion 27, the ends of which extend through the lower slots 25 of housing 23. On each of said lower shank portions 27 is a substantially V shaped notch 31 adapted to removably receive, when any of said control members is moved to a lower position, a locking bar 32. The ends of the lower shanks 27 of said control members are rounded at 33 to act as a cam surface on locking bar 32. The locking bar 32 is pivotally attached to the inner and outer rounded stubs 34 and 35 respectively of a plate 36 rotatably attached to the housing 23. A pair of stops 37 on opposite outer lower portions of the housing 23 confine the locking bar 32 to desired position. Springs 38 are attached on the upper ends 39 to housing 23 and on the lower ends 40 to control members 28 to normally hold them in non-operating position.

Attached to the inner rounded stub 34 is a lower arm 41 which is connected by a link 42 to an upper arm 43 which is attached to rod 19.

In use let us assume that the user desires to dictate. A wax record 22 is placed on the mandrel 13. The user then pushes the button 29 marked "Dictate." When pressure is applied to said button 29 the control member 28 moves downwardly until the front surface 44 of body portion 30 contacts the plate 36. The front surface 44 has been cut upon such a desired angle as to pivot the plate 36 to the same angle and thus turn the stub 34, and through arms 41 and 43 and linkage 42 the rod 19.

The rod 19 has a key way 44 in which travels a roller key 45. The roller key 45 is attached to a holding member 46 and extends through a groove

47 in bushing 48. The holding member 46 has a pair of spaced depending ears 49. A roller 50 extending between the ears 49 is rotatably mounted in said ears. A pin 51 spaced from said roller 50 extends between said ears 49 with its ends extending beyond said ears.

Two paws 52 are pivotally attached to a pin 53 which is attached to opposite sides 54 of the carriage 18. Spacers 55 surround pin 53 and retain paws 52 in desired separated position. The paws 52 have cam surfaces adapted to cooperate with pin 51. Springs 56 are attached on one end to paws 52 and on their other end to a fixed portion of the carriage 18.

When the rod 19 is actuated as heretofore described, the roller key 45 moves the holding member 46 so that pin 51 pushes the paws 52 downwardly to their lowest position, permitting the cutting stylus 21 to freely contact the record 22.

When the "listen" button 29 is pressed by the user the control member 28 attached to said pressed button 29 moves downwardly until the front surface 44 of its body portion 30 contacts the plate 36 to move it to the same angle of said front surface, which would be in substantially the opposite direction from the dictate button and its control member. The stub 34 is then moved, and through arms 41 and 43 and linkage 42, rod 19 is moved in the opposite direction. Roller key 45 then moves holding member 46 to such a position that one of the paws 52 is free from contact with pin 51 and spring 56 pulls said paw upwardly. In moving upwardly, said paw 52 engages lip 57 of pan 58 and permits sound reproducing needle 59 to move downwardly to engage the record 22.

A support 60 is pivotally attached to the carriage 18 and has a depending foot 61 having a cam portion adapted to cooperate with roller 50. Attached to said support 60 is a half nut 62 adapted to engage the screw threads of shaft 63 which is rotatably attached to the upstanding portions 20 of frame 10.

When the neutral button 29 is pressed by the user, the control member 28 attached to said pressed button 29 moves downwardly until the front surface 44 of its body portion 30 contacts the plate 36 to the same angle as said front surface. The stub 34 is then moved and through arms 41 and 43 and linkage 42, rod 19 is moved. Roller key 45 then moves holding member 46 so that pin 51 releases contact with both paws 52 and permits springs 56 to pull both paws 52 upwardly, so that one paw engages lip 57 of pan 58 and the other paw 52 engages lip 64 of disc 65. While this is being done roller 50 pushes foot 61 so as to pivot support 60 and lift half nut 62 from engagement with shaft 63. This permits the carriage 18 to be moved laterally on rod 19.

When the machine is in dictating or listening position the roller 50 is moved to such a position as to permit spring 66, which extends between carriage 18 and support 60, to pull the support downwardly so as to permit engagement of half nut 62 with screw threads of shaft 63, to provide carriage 18 with its sound member 17 for movement on record 22.

Attached to the body portion 30 of the neutral control member 28 is a stop arm 67 extending upwardly through an opening 69 in the frame 10 and positioned to the rear of the record 22. When the neutral button 29 is pushed, the control member 28 attached thereto is moved downwardly and carries stop arm 67 downwardly so that the record 22 may be removed from or

10 inserted onto the mandrel 13. When either the dictating or listening control members is in operating position the neutral control member is released from operating position as heretofore 5 set forth, and said neutral control member 28 holds stop arm 67 in an upward position with its upper end higher above the frame 10 so as to prevent a record 22 from being removed from or placed onto the mandrel 13. This prevents 10 damage to stylus, and record.

For the ejection of the record 22 from the mandrel 13, I provide a pusher or hand 68 positioned to engage the front edge of the record 22. The pusher slidably extends into an opening 69 15 in frame 10. To the lower portion of the pusher 68 an elbow 70 is pivotally attached. To substantially the middle of said elbow a fulcrum or pivot 71 is provided, said pivot being attached to the under portion of said frame 10. Surrounding the outer end portion of said elbow 70 is the lower loop portion 72 of a lever 73. The lever is pivotally attached at the fulcrum point 74 to the under portion of the frame 10. The other end of the lever 73 extends beyond the edge of 20 the frame 10 and through the casing 75. A button 76 is provided at the end of said lever for manual operation.

A bar 77 is slidable within sleeve 78 attached to the under portion of said frame. The front end of said bar 77 is held in constant contact with the elbow 70 above the pivot point 71 by means of spring 79 attached on one end to said bar 77 and on the other end to a stationary part of the frame 10. The bar extends rearwardly 35 to a door 80. Said door 80 has an aperture 81, and has an integral extension 82 attached to inner stub 34.

When either the "dictate" or "listen" buttons 29 are pushed in the control members 28 attached thereto move plate 36 and stub 34 so as to swing said door in one or the other direction in front of the outer end of bar 77 and prevent the bar from further movement. When the neutral button 29 is actuated, its control member 28 moves plate 36 and stub 34 so as to swing the door 80 to such a position that aperture 81 is ready to receive the outer end of bar 77. In this position button 76 can be pushed downwardly to actuate lever 73 and elbow 70 to move pusher 68 to eject the record 22 because the outer end of bar 77 may enter opening 81 in door 80. Ejection of the record may therefore only take place when the machine is in neutral position.

A shade 83 has a substantially flat body portion 84 and end portions 85 attached to rounded stubs 34 and 35. The shade 83 has three spaced apertures 86. Attached to the housing 23 is an electric light bulb 87 connected by suitable wires to an electrical source of supply. The light bulb 87 is positioned so as to be substantially shaded in one direction by shade 83. On the other side of the shade 83 are a plurality of jewels 88 positioned immediately adjacent or below the push buttons 29. The jewels for better indication 60 might well be differently colored. In use when the neutral button 29 is pushed and its control member 28 moves against plate 36, rounded stubs 65 34 and 35 are turned so as to swing shade 83 to a desired position. In this position one of the openings 86 receives the light from bulb 87 and directs the light to illuminate the jewel 88 under the neutral button. When the listen or dictate buttons are respectively pushed the same operation occurs, except that shade 83 is swung so as to expose a different opening 86 to light bulb 87

and thus direct light to the jewel adjacent the listen or dictate button respectively.

Having thus described my invention, I claim:

In a push button means for dictating machines having a record ejector, a housing, a dictate push button control member, a listen push button control member, a neutral push button control member, said control members slidably mounted on said housing, each of said control members having a surface cut on a different desired angle, 10 a plate rotatably attached to said housing, a door

with an opening, said door attached to said plate, each of said control members adapted upon pressure to contact said plate with its surface and pivot said plate in accordance with the angle of said surface, said dictate and listen control members adapted to pivot said plate and swing said door so as to block the operation of the record ejector, said neutral control member adapted to pivot said plate and permit the record ejector to operate through the opening in said door.

BENJAMIN A. SCHIFF.
